(57) **CLAIM**

The ornamental design for a bottle, as shown and described.

DESCRIPTION

FIG. 1 is a top, front perspective view of a bottle showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a cross section view taken along the line 8—8 in FIG. 2;

FIG. 9 is a cross section view taken along the line 9—9 FIG. 2; and,

FIG. 10 is a top, front perspective view of the bottle of FIG. 1, shown with the cap open and removed.

The broken lines in the drawings illustrate the details of the design that form no part of the claim.
